[57] CLAIM

The ornamental design for an air conditioner cover, as shown and described.

DESCRIPTION

FIG. 1 is a front elevational view of an air conditioner cover embodying my new design;

FIG. 2 is a top plan view thereof;

FIG. 3 is a bottom plan view thereof;

FIG. 4 is a left side elevational view thereof; the right side being a mirror image of the side shown;

FIG. 5 is a rear elevational view thereof; and

FIG. 6 is a cross sectional view taken on line 6—6 of FIG. 1.
